Specification of Letters Patent.

Patented July 4, 1916.

Application filed November 21, 1913. Serial No. 802,217.

To all whom it may concern:

Be it known that I, MONROE GUETT, a citizen of the United States, and a resident of Hartford, in the county of Hartford and 5 State of Connecticut, have invented certain new and useful Improvements in Switches, of which the following is a specification.

The object of this invention is to improve the construction of snap switch mechanisms, 10 particularly in respect of that part which has to do with the operation and control of the blades.

Referring to the drawings—Figure 1 is a side view of a complete switch embodying 15 the invention, the receptacle being shown in section. Fig. 2 is a view partly in section, taken on the line 2—2 of Fig. 4, looking in the direction of the arrow. Fig. 3 is a similar view showing the blade carrier in place. 20 Fig. 4 is an end view of the complete mechanism. Fig. 5 is a side view of the mechanism showing the blade about to be released. Figs. 6 and 7 are detail views in side and 25 end view of the rock bar. Figs. 8 and 9 are similar views of the blade carrier.

The invention is shown as embodied in a push button switch wherein *a* denotes the receptacle, *b*, *b*, the stationary contacts therein, and *c* denotes generally the switch mechanism. The switch mechanism is mounted 30 on a frame which may conveniently be a box-like structure having front and rear plates 2, 3, an upper cross plate 4, and bottom cross plates 5, 5, forming the feet on 35 which the mechanism rests in the receptacle. The particular structure of the frame is not material, though I have found that here illustrated and described a satisfactory one.

10 is the spindle supported in the side plates 2, 3, and projecting to the front of the latter.

15 is the rock bar mounted to turn on the spindle and to the ends of which the push buttons *d*, *e*, are connected. It is also provided with a double-ended dog 16 and a spring arm 17.

20 is the blade carrier fast on the spindle at the front of the front frame plate 3, and provided with a spring arm 21 co-operatively

positioned with relation to the spring arm 17 50 on the rock bar 15, these spring arms being located between the ends of a spring 22 coiled on the spindle and operating in the usual way to tension the spring during the initial movement of the operating handle, 55 that is to say, one of the push buttons, during which time the spring arm connected with the push button moves while the spring arm connected with the blades remains stationary. A blade *f* is secured to the blade 60 carrier.

Projecting to the rear from the lower edge of the blade carrier 20, and at each end thereof, are locking projections 23, 24, which engage, one at a time, lugs 25, 26, on a lock 65 plate 27 which is supported on a pin 27^a projecting from the rear of the front frame plate 3 and provided with shoulders 28, 29, against which the ends of the dog 16 act. A spring 33, bearing on a plate 32, which at 70 its rear end is supported in the frame plate 2 and at its front end rests on pins 30, 31 projecting from the lock plate 27, normally holds the lock plate so that its lugs 25, 26, 75 may engage with the locking projections 23, 24. The support of the lock plate on the pin 27^a is sufficiently free and loose to permit of its movement in various directions. For instance, it swings laterally under the action of the dog 16 to disengage the lugs 80 25, 26 from the locking projections 23, 24 of the blade carrier, and it moves to the rear bodily, or may be tilted sufficiently to permit the locking projections 23, 24 to move by the lugs 25, 26, after which the spring 33 85 moves the lock plate back to normal position in order that one of the locking projections 23, 24, may be engaged with one of the lugs 25, 26.

Assuming the parts to be in the position 90 shown in Figs. 1, 2, 3 and 4, the operation is as follows:—Pressure on the button *d* throws the rock bar 15 until the left hand end of the dog 16 acts upon the shoulder 28 of the lock plate 27, rocking it on its pivot until the lug 95 25 is withdrawn from under the locking projection 23 of the blade carrier 20. This action of the rock bar through the spring

arm 17 has tensioned the spring, which upon the release of the blade carrier throws the blades to their other extreme position. As the blades approach the end of this movement, the locking projection 24 has a camming action on the end of the lug 25, swinging the lock plate 27 to the rear, enabling the rock bar to move to position, after which the spring 33 bearing on the plate 32 which 10 presses on the ends of the pins 30, 31, throws the lock plate back to normal position, moving the lug 26 under the locking projection 24. The push button *d* is now depressed and *e* elevated; and pressure on *e* will cause a 15 similar action of the parts in the reverse direction.

I do not desire it to be understood that the structure is limited to use in a push button switch, or that the exact construction 20 here illustrated and described may not be altered or modified to suit special conditions. I have merely selected this embodiment of the invention for illustration and description.

I claim:

25 1. In an electric snap switch, an operating handle, an actuator operatively connected therewith, a blade carrier, a pivoted lock plate, interengaging parts on the blade carrier and lock plate, coöperating parts on 30 said actuator and lock plate to move the latter to release the blade carrier, and means for producing relative motion between said blade carrier and lock plate in a direction at an angle to the plane of rotation of the 35 said blade carrier, said means comprising coöperating parts on said blade carrier and lock plate, and means to return said blade carrier and lock plate to normal position.

40 2. An electric switch mechanism including, in combination with the blades and oscillating blade carrier, a pivoted lock plate, manual means for moving said lock plate on its pivot in a plane substantially parallel to the plane of rotation of the blade carrier, 45 and automatically operating means to produce relative motion between the lock plate and blade carrier in a direction at an angle to the plane of rotation of the latter.

50 3. In an electric switch, the combination with the blades and an oscillating blade carrier, of a lock plate supported for movement in different vertical planes, manual means for moving said plate in one plane, and automatically operating means for moving 55 said plate in another plane.

4. In an electric switch, the combination with an oscillating blade carrier, of a lock plate, a support therefor to permit movement in a plurality of directions, means for 60 holding said lock plate in normal position in operative relation with said blade carrier, interengaging parts on said blade carrier and lock plate, manually operated means for moving said lock plate to release said blade

carrier, and automatically operating means 65 to move said lock plate out of normal position.

5. In an electric snap switch, the combination with an operating handle, an oscillating blade carrier, of a lock plate, a support 70 therefor to permit movement in a plurality of directions, means for holding said lock plate in normal position in operative relation with said blade carrier, engaging parts on said lock plate and said blade carrier, 75 means connected with said handle to move said lock plate to release said blade carrier, and means on the blade carrier to move said lock plate out of normal position.

6. In an electric snap switch, a frame and 80 a spindle mounted therein, a blade carrier mounted for turning movement on said spindle, a lock plate engageable with said blade carrier to hold it against movement, a pin upon which said lock plate is loosely 85 supported, means for holding said lock plate in normal position in operative relation with respect to said blade carrier, an actuator mounted on the spindle and co-operating with said lock plate to move it to 90 release said blade carrier, an operating handle connected with the actuator, and cam surfaces on said blade carrier co-operating with said lock plate to move it out of normal position as said blade carrier approaches 95 either of its extreme positions.

7. In an electrical snap switch, a frame and a spindle mounted therein, a blade carrier mounted for turning movement on said spindle between two extreme positions, a 100 lock plate, interengaging parts on said blade carrier and lock plate to hold the former in either of its extreme positions, a rock bar mounted for turning on said spindle, an operating handle therefor, co-operatively arranged spring arms on said rock bar and blade carrier, a spring connected with said spring arm and forming a driving connection between said parts, dogs on said rock bar co-operating with said lock plate, one at 110 a time, to move it on its pivot and release said blade carrier, and means on the blade carrier engaging said lock plate to move it to the rear as said blade carrier approaches its extreme position, and a spring to return 115 the lock plate to normal position after the blade carrier has reached its extreme position.

8. In an electric snap switch, the combination with the blades and an oscillating pole 120 carrier provided with rearwardly extending locking projections at each end of its lower edge, of a lock plate supported in the frame at the rear of the blade carrier and having forwardly projecting locks adapted to co-operate with the projections on the blade carrier to hold the latter against movement, a rock bar and operating handles connected 125

therewith, dogs on said rock bar coöperating with said lock plate to swing it laterally on its support to release said blade carrier, a spring connecting said rock bar and blade carrier and operative to move the latter when it is released, and means on said blade carrier engaging the lugs on the lock plate to move the latter to the rear as the blade

carrier moves to one of its extreme positions, and a spring to return the lock plate to normal position into engaging relation with said blade carrier. ¹⁰
